Attorney

UNITED STATES PATENT OFFICE.

THEOPHILUS R. HYDE, JR., OF WATERBURY, CONNECTICUT, ASSIGNOR TO SCOVILL MANUFACTURING COMPANY, OF WATERBURY, CONNECTICUT, A CORPORATION OF CONNECTICUT.

STUD.

SPECIFICATION forming part of Letters Patent No. 739,677, dated September 22, 1903.

Application filed April 14, 1903. Serial No. 152,528. (No model.)

To all whom it may concern:

Be it known that I, THEOPHILUS R. HYDE, Jr., a citizen of the United States, residing at Waterbury, in the county of New Haven and 5 State of Connecticut, have invented a certain new and useful Improvement in Studs, of which the following is a full, clear, and exact description.

This invention relates to that class of garment-fastening devices most commonly used on gloves and known as "snap-fasteners" and composed of a socket member and a co-operating member known as a "stud" and sometimes called a "head," and the invention herein relates to the stud or head.

The object of the invention is to construct a spring-stud of what is known as the "bird-cage" variety in a simple and economical way, so as to permit a limited play of the arms of 20 the spring and prevent their displacement and the overcoming of their elastic limit.

The invention consists of a three-part stud comprising a spring-head of bulbous shape, having its spring-arms bent to form a base-flange and connected by a collet to an eyelet, which latter has a rim or bead projecting from its barrel sufficiently far into the spring-head in the plane of its base-flange to prevent the displacement of the arms of the spring-head, 25 while admitting of sufficient movement to insure the necessary resilience in engaging the complementary socket member, all as I will proceed now more particularly to set forth and finally claim.

35 In the accompanying drawings, illustrating the invention, in the several figures of which like parts are similarly designated, Figure 1 is a plan view of the spring-head blank. Fig. 2 shows the component parts of the stud 40 ready for assembling. Fig. 3 is a side elevation of the finished stud. Fig. 4 is a longitudinal section of the finished stud. Fig. 5 is a top plan view of the finished stud. Fig. 6 is a longitudinal section of the stud applied 45 to fabric by an open washer. Fig. 7 is a lon-

gitudinal section of the stud applied to fabric by a closed washer.

The spring-head may be formed in any of a variety of ways—as, for example, by the use of a blank 1, having radiating arms, Fig. 1, 50 which is bent to form a bulbous head 2, the ends of the arms being bent to form a base-flange 3. (See Fig. 2.)

The fastening device is an open-end eyelet 4, having a flange 5, with a rim or bead 6 projecting above the flange in the line of the barrel, so that when the spring-head and the eyelet are assembled, as in Fig. 4, this rim or bead will enter the spring-head in the plane of its base-flange, and while admitting of a limited movement of the arms of the spring-head in order to give the spring-head sufficient resilience to be entered into and withdrawn from the socket will also prevent such compression of the said arms as to overcome the elastic 65 limit of the spring-head. The spring-head and the eyelet are united by means of a collet 7, engaging their respective flanges, said collet being a flanged annulus to which the spring-head is first secured, as in Fig. 2, and 70 then its flange bent under the flange of the eyelet, as shown in Fig. 4.

The stud may be applied to a fabric or garment 8 in any usual or approved way and with an open washer 9, Fig. 6, or a covered washer 10, Fig. 7, to receive the upset end of the eyelet, or the washer may be dispensed with where the fabric or the material of the garment is sufficiently thick or heavy to take the strains, and any desired form or construction of washer may be employed where necessary or desired.

What I claim is—

1. A three-part stud, comprising a bulbous spring-head of so-called "bird-cage" form, 85 having its spring-arms bent to form a base-flange, a fastening-eyelet having a rim or bead projecting in line of its barrel and extending into said spring-head in the plane of its base-flange, and a collet engaging the eyelet and 90

the base-flange of the spring-head to unite them.

2. A three-part stud, comprising a bulbous spring-head of so-called "bird-cage" form, 5 having its spring-arms bent to form a base-flange, a fastening-eyelet having a rim or bead projecting in line of its barrel and extending into said spring-head in the plane of its base-flange, and a collet engaging the eyelet and

the base-flange of the spring-head to unite them, combined with a washer to receive the upset end of the eyelet.

In testimony whereof I have hereunto set my hand this 13th day of April, A. D. 1903.

THEOPHILUS R. HYDE, JR.
